UNITED STATES PATENT OFFICE.

JAMES P. SNEDDON, OF BAYONNE, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

1,318,509.

Specification of Letters Patent. Patented Oct. 14, 1919.

Application filed July 8, 1916. Serial No. 108,093.

To all whom it may concern:

Be it known that I, JAMES P. SNEDDON, a citizen of the United States, residing at Bayonne, in the county of Hudson and State of New Jersey, have invented certain new and useful Improvements in Water-Tube Boilers, of which the following is a specification.

My invention relates to water tube boilers and more particularly to those of the Stirling type in which upper transverse steam and water drums are connected by banks of tubes to a lower mud drum or drums, the gases being directed by baffling in serial 10 passes over the banks. The general object of the invention is to provide a construction which will prevent or reduce priming. In the embodiment shown the steam is taken from dry pipes in the rear drum through 15 circulating nipples to a collecting pipe in the middle drum and thence to the steam outlet. The invention is especially adapted for boilers which are in service and have a steam outlet connection from the middle 20 drum, as the steam may be led from the rear drum without altering the steam connections leading from the boiler.

The invention will be understood by reference to the accompanying drawings in 25 which Figure 1 is a vertical longitudinal section showing sufficient of the parts of a boiler to explain the invention; Fig. 2 a longitudinal section through the rear steam and water drum; Fig. 3 a similar view 30 through the middle steam and water drum; and Fig. 4 a view illustrating a slight modification. Similar reference numerals indicate similar parts in the several views.

Referring to the drawings the numerals 1, 2 and 3 designate the front, middle and rear transverse steam and water drums of 35 a Stirling boiler. These drums are connected by banks of tubes 4, 5 and 6 to a mud drum. Baffling shown at 7, 8 and 9 is arranged to direct the gases, rising from 40 the furnace 10, in serial passes over the banks to the offtake 11. The water spaces of the drums 1 and 2 are connected by circulators 12. In the modification shown in 45 Fig. 4 circulators 13 also connect the water spaces of the drums 2 and 3. In the form shown in Fig. 1 the circulators 13 are omitted. The steam spaces of the drums 1 and 2 are connected by circulators 14, and

the steam spaces of drums 2 and 3 are connected by circulators 15.

In the steam space of the rear drum, and near the ends of the drum, are placed dry pipes 16 to which are connected circulating nipples 17 which lead to a collecting pipe 18 in the steam space of the middle steam and water drum 2. The steam is discharged through the outlet connection 19, which is located in the usual position on the middle steam and water drum and leads from the collecting pipe 18 extending longitudinally through the drum 2, the pipe 18 being closed against entrance of steam direct from the drum 2. The collecting pipe 18 is provided with a drain pipe 20 through which any water pocketed in the collecting pipe may be discharged when the boiler is started up.

In the described arrangement the steam from the front steam and water drum 1 is taken through the circulators 14 to the middle steam and water drum 2 and from the latter is taken through the circulators 15 to the rear steam and water drum. From the drum 3 the steam passes through the circulating nipples to the collecting pipe 18 from which it is discharged through the outlet connection.

The feed water is delivered to the rear steam and water drum through a pipe 21 which discharges into a trough 22.

What I claim and desire to secure by Letters Patent of the United States is:—

1. A water tube boiler having three transverse steam and water drums connected by banks of tubes to a transverse water chamber, steam and water circulators connecting the steam and water drums, a dry pipe near each end of one of the steam and water drums, a steam collecting pipe in one of the other steam and water drums, and nipples connecting the said dry pipes with said collecting pipe, and a steam outlet connection from said collecting pipe.

2. A water tube boiler having three transverse steam and water drums connected by banks of tubes to a transverse water chamber, steam and water circulators connecting the steam and water drums, a dry pipe near each end of one of the steam and water drums, a steam collecting pipe in one of the other steam and water drums, nipples connecting the said dry pipes with the ends

of the collecting pipe, and a steam outlet connection from said collecting pipe.

3. A water tube boiler having three transverse steam and water drums connected by 5 banks of tubes to a transverse water chamber, steam and water circulators connecting the steam and water drums, the steam circulators delivering all of the steam to the rear drum, a dry pipe at each end of the 10 rear steam and water drum, a steam collecting pipe in the middle steam and water

drum, nipples connecting said dry pipes with the ends of said collecting pipe, and a steam outlet connection for said collecting pipe.

In testimony whereof I have hereunto signed my name in the presence of two subscribing witnesses.

JAMES P. SNEDDON.
